(Continued)

Primary Examiner — Jennifer L Rempfer**CLAIM**

(57) The ornamental design for a dog trainer remote control as shown and described.

DESCRIPTION

FIG. 1 is a front, left and top perspective view of a dog trainer remote control showing my design;
FIG. 2 is a rear, right and bottom perspective view thereof;
FIG. 3 is a front elevation view thereof;
FIG. 4 is a rear elevation view thereof;
FIG. 5 is a left-side elevation view thereof;
FIG. 6 is a right-side elevation view thereof;
FIG. 7 is a top plan view thereof; and,
FIG. 8 is a bottom plan view thereof.

The broken lines immediately adjacent the claimed surfaces depict the bounds of the claimed design, whereas all remaining broken lines depict portions of the dog trainer remote, all of which form no part of the claimed design.

1 Claim, 8 Drawing Sheets(56)
